SORTING MACHINE FOR RECORD CARDS

Filed March 20, 1929 4 Sheets-Sheet 4

UNITED STATES PATENT OFFICE

EUGENE A. FORD, OF SCARSDALE, NEW YORK, ASSIGNOR TO THE TABULATING MACHINE COMPANY, OF ENDICOTT, NEW YORK, A CORPORATION OF NEW JERSEY.

SORTING MACHINE FOR RECORD CARDS

Application filed March 20, 1929. Serial No. 348,395.

This invention relates to machines especially adapted for sorting cards used in tabulating machines, such, for instance, as the well known Hollerith.

Index points are formed by punching holes through the cards, the value and character of the information conveyed by each hole being dependent upon its exact location on the card. The index points are arranged in vertical columns and certain columns contain punched index holes designating the kind or class to which the card belongs.

As it would be a tedious task to sort the cards by hand, into desired classes or groups before running them through the tabulating machines, sorting machines have been designated to do the classifying automatically, and that is the class of machine to which the present invention belongs, being an improvement on the machine described in detail in the copending application of applicant, Serial No. 329,388, filed December 31, 1928, which discloses a sorter of the horizontal type designed to sort the cards electrically and deposit each class in a station.

The present invention pertains especially to the method of controlling the receiving ends of the blades which conduct each card to its station after the selecting or analyzing device indicates to which station it should go.

In the drawings:

Fig. 1 is a perspective view of an assembled machine embodying the present improvements;

Fig. 2 is a transverse sectional view illustrating the card feeding mechanism and the controlling devices for the card distributing mechanism;

Fig. 3 is a plan view of the controlling devices for card distributing mechanism, on line 3—3 of Fig. 2;

Fig. 4 is a diagrammatic perspective view illustrating the manner in which a record card passage is effected upon the analyzing of an index point perforation.

Referring to Fig. 1 which shows a perspective view of the machine the frame 30 is mounted on legs 31. Underneath the frame is a shelf or sub-frame 32 supporting the motor 33 which drives the machine shafts by

the usual belt and pulley arrangement (not shown).

Box 34 underneath the frame 30 contains the relays, fuses, and electrical connections, current from the outside source being admitted to or cut out from the machine by switch button 35 and 36.

When a group of record cards 37 have been properly stacked the stack is placed in the feed magazine 38 with plate 39 on top of the stack. This plate is used so that when there are only a few cards left in the stack there will be sufficient weight on them to prevent them from being displaced from true position by the rapid action of the picker mechanism.

To arrange for sorting the record cards in accordance with the index points in a selected column, the operator, by means of a crank handle 40 moves a contact brush 41 laterally (Fig. 2) so it will traverse the desired index column on the cards as they pass under it. The machine is then started in operation in order that a picker 42 may feed cards singly from the bottom of the stack to the analyzer, when passage of the card is directed between the usual succeeding pairs of conveyor rollers into one of the thirteen receiving stations R, 12, 11, 0, 1, 2, 3, 4, 5, 6, 7, 8, 9 (see Fig. 1). The receiving stations each consists of a compartment formed by vertical walls 28 and a back plate 29 and in which is inserted in each station the usual resiliently mounted tray for receiving the cards directed to that particular station.

Card feed mechanism

Any suitable feed mechanism may be employed for feeding record cards to the analyzing mechanism and preferably comprises an arm 43 to which is connected a link 44 eccentrically mounted on a drive shaft 45. Each reciprocation of the arm 43 effects a similar movement to a plate 46 which carries picker knife 42. The latter picks a card from the bottom of the stack and feeds it through the usual card throat, the card being then directed by feed rolls 47 to the analyzing device, comprising, in the present instance, a brush 41 and a conducting roll 48, the brush 41

being insulated from the roll 48 by an integral portion of the card so that an electrical contact therewith may be effected through a perforation in the record card, this, of course, occurring at differential times during a card cycle, contact being effected sooner or later depending upon the index point perforation in the column analyzed. Brush 41 and contact roll 48 are in serial electrical connection with a magnet 49 and a source of current supply thus permitting energization of magnet 49 at differential times in the card cycle.

15 *Distributing system*

The principle of the distributing system may be readily understood from Figs. 2, 3 and 4 in which 48 designates the brass contact cylinder extending crosswise of the machine to provide contact with the brush 41 in a selected card column. 50 are a plurality of thin flexible blades made of steel, brass, or any other suitable material one of their ends being spring biased downwards and their other ends being of successive lengths so as to terminate at the respective card stations to direct the record card thereto. The blades 50 overlap each other and have their terminations 51 in direct contact with actuating levers 52. The levers 52 are pivoted upon a common rod 53 and are each urged downwardly by respective springs 54 to provide continuous contact with the periphery of the related cam 55.

35 A series of such cams 55 are provided and are carried by a drive shaft 59 so that they are driven as a unit and in synchronism with the feeding of the card beneath brush 41. Each cam 55 may be said to have a cam portion 56 which continues to form a concentric portion 57 terminating at 58 to permit a drop for the associated levers 52 under the action of its biasing spring 54. It will be observed that the cam edges 56 of all the cams 55 are similarly disposed on the shaft 59 so that an initial rotation of the latter will elevate all the levers 52 and likewise all of the ends of the blades 50. However, the drop portions 58 of the series of cams are spirally arranged so that while the levers 52 and ends of blades 50 are initially and simultaneously elevated, the levers 52 drop under the action of their biasing springs 54 seriatim. In further detail, it is obvious that an initial operation of shaft 59 will elevate the terminations 51 of all the blades 50 so that upon continued rotation of the cam shaft 59 the drop 58 of the cam associated with blade 50₁, will permit the related lever 52 to be urged downwardly by its spring, the blade 50₁, following. Since the blades above blade 50₁, will be held up by the concentric portions of their cams, an opening will be provided between blades 50₁, and 50₂. This opening is effected during 60 the card feeding cycle at the time the "9"

index point is presented to the brush 41. During the subsequent part of the cycle the remaining cams permit the blades through their related levers to drop successively to thereby form card passages between adjacent blades 70 successively and coincident with the presentation of the index points to the analyzing brush.

From the foregoing it will be clear that the passages are formed successively and that the openings are of short duration since they are dependent upon the angular displacement of the drops 58 of the series of cams. It is essential, however, that if an index point perforation is presented to the brush 41 that the separation between the adjacent blades be retained until the record card passes therebetween. In the preferred embodiment this control is effected by magnet 49 and associated devices now to be explained.

75 The magnet armature 60 (Fig. 2) is pivoted at 61 and functions as a latch for a plate 62 pivoted at 63 and which is provided with a shelf 64 adapted to be shifted by a spring 66 to engage under projections 65 of the levers which are in elevated position prior to the energization of magnet 49.

80 In more detail, when the machine is sorting a promiscuous stack of cards each card as it comes from the feeding mechanism is passed over the cylinder 48 with brush 41 bearing on the top surface of the card. As the cards leave the brush they pass over a plate 66^a and beneath a spring urged plate 67. If a card contains no hole in the column analyzed it will pass above the uppermost blade 50₁₂ into the last receiving station designated R, or "reject". The usual conveying rollers are provided for transporting the cards to the several stations, a pair of which are shown at 68 in Fig. 2, the rest being omitted as they are well known in the art.

85 If, however, brush 41 finds a hole in the card it will complete the electric circuit by making contact with cylinder 48, magnet 49 will be energized, armature 60 drawn down and plate 62 unlatched and as shelf 64 engages under certain levers 52 which have not been previously drawn down by their springs 54, the remaining levers 52 and the corresponding blades will be held up. The blades associated with the levers 52 which have dropped will, of course, bend at their ends to follow said levers, thereby effecting a passage between certain adjacent blades. This passage will be kept open due to the unlatched condition of plate 62. If the "2" index point should be perforated the condition shown in Fig. 4 will arise wherein it will be seen that certain blades will be retained elevated and certain ones have previously dropped. This condition will be retained so that further progress of the card to the left will direct it into the passage formed between the first and second blade. As the card passes

between successive pairs of rollers it will be confined to that passage that terminates in station 2. It is evident that the destination of each card depends upon which opening is effected between a pair of adjacent blades at the instant the magnet is energized, and that depends upon the location of the hole in the card.

The index points are fed bottom first and the brushes pass over the index points in any column in the order, 9, 8, 7, 6, 5, 4, 3, 2, 1, 0, followed by the extra positions, as for instance 11 and 12, in Fig. 4. These extra positions correspond to stations 11 and 12 respectively.

A restoring cam 69 revolving with the cams 50 rocks a bail 70 to restore plate 62 to re-latched position after the passage of each card. In the event that the springs 54 should be sluggish and not act quickly enough to depress the levers 52 which have been released by their related cams a bevel edge 71 of shelf 64 will coact with inclined edges 72 of the feet 65 of the released levers 52 and positively lower and lock them in lowered position. The corresponding blades 50 on account of their spring bias will follow the lowered levers to effect the desired card passage.

The ends 51 of the blades 50 are so positioned relatively to the brush 41 that if the brush finds a hole at an index point the magnet will be energized to shift the shelf 64 under the elevated levers 52 before the lever 52 next in order to be released drops off the high part of its related cam. As the foot 65 of the lever 52 drops off the cam it will coact with shelf 64 to retain certain adjacent blades open permitting the directed card to pass therebetween.

While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention therefore to be limited only as indicated by the scope of the following claims:

1. In a record card sorting machine comprising in combination with a plurality of card receiving pockets, a plurality of overlapping card sorting blades adapted to guide record cards to the desired card pocket, means for initially elevating the terminations of said blades and then separating the blades seriatim, and means under control of said record card for retaining the separation between the adjacent blades.

2. In a record card sorting machine comprising in combination with a plurality of overlapping sorting blades forming card passages, and means for initially elevating said

blades and then separating the blades seriatim to successively form card passages.

3. In a record card sorting machine, a plurality of blades forming passages for record cards, a rotary mechanism initially shifting all of said blades and then separating adjacent blades to successively form card passages and means under control of said record card to retain the separation between separated adjacent blades.

4. In a card sorting machine, a plurality of receiving stations, a plurality of sorting blades for forming passages to said stations, cam means for initially shifting all of said blades and then separating adjacent blades, and means under control of said record card for retaining certain blades in shifted position to form a desired card passage.

5. In a card sorting machine, a plurality of receiving stations, cam means, a plurality of sorting blades for forming passages to said stations said blades being biased against the cam means, said cam means initially shifting all of said blades and then separating said blades to successively form card passages between adjacent separated blades.

6. In a sorting machine for record cards having index points, a plurality of receiving stations, a plurality of card sorting blades, means for initially shifting all of said blades collectively and then releasing them individually and successively and means for preventing retraction of certain of said blades to retain a card passage between certain adjacent blades.

7. In a sorting machine for record cards having index points, a plurality of receiving stations, a plurality of card sorting blades, means for simultaneously shifting all of said blades and then releasing them individually and successively, a movable member under control of said record card and means whereby said movable member prevents retraction of certain blades to retain a card passage between certain adjacent blades.

8. In a card sorting machine, a plurality of receiving stations, a plurality of card sorting blades for forming card passages to said stations, said blades being biased by their own resiliency so as to tend to retract or assume their normal position when shifted therefrom, means for shifting all of said blades simultaneously and successively releasing them individually to normal and means under control of said record card for preventing the retraction of certain blades by their own resiliency to their normal positions to form a card passage between said blades.

9. In a card sorting machine, a plurality of card receiving stations, a plurality of card sorting blades and a rotary mechanism for causing all of said blades to be simultaneously shifted and successively released whereby said blades are successively retracted to their normal positions.

10. In a record card sorting machine, a plurality of card receiving stations, a plurality of card sorting blades and a rotary mechanism for causing all of said blades to be simultaneously shifted and successively released whereby said blades are successively retracted to their normal positions and means under control of said record card for preventing a retraction of certain blades to form a card passage between said blades. 75
11. In a sorting machine for record cards having index points, a plurality of card receiving stations, an analyzing device, a plurality of card sorting blades means whereby said blades are initially shifted and successively released to successively form card passages, said card passages being formed coincident with the presentation of the index points of said record card to the analyzing devices. 130
12. In a sorting machine for record cards having index points, a plurality of card receiving stations, a plurality of card sorting blades said blades adapted to form card passages to said stations, an analyzing device and means whereby said blades are successively released to normal to form a card passage for each index point of the record card presented to said analyzing brush. 135
13. In a machine for sorting record cards having index points, an analyzing device, a plurality of card receiving stations, a plurality of sorting blades adapted to form card passages to said stations, and means whereby adjacent blades are successively released to normal to form card passages successively and coincident with the presentation of each index point to the analyzing device. 140
14. In a machine for sorting cards having index points, an analyzing device, a plurality of card receiving stations, a plurality of blades adapted to be separated to form card passages to said stations, means contacting with said blades whereby adjacent blades are separated to form card passages successively and coincident with the presentation of each index point to the analyzing device, and means for retaining a card passage during the operation of said means until the record card analyzed is directed thereto. 145
15. In a machine for sorting cards, a plurality of card receiving stations, a plurality of blades adapted to be separated to form card passages for the cards to the receiving stations and means for initially shifting all of said blades and to subsequently permit the retraction of the blades seriatim to thereby successively form card passages between adjacent blades. 150
16. In a machine for sorting cards, including in combination a rotary device comprising a series of cams, a card distributing mechanism including a series of superimposed assorting blades having ends terminating at the same line and adapted to be biased in order to follow the contour of their related cams whereby card passages are successively formed between adjacent blades. 155
17. In a machine for sorting cards comprising a plurality of card distributing stations, a plurality of card sorting blades, a corresponding number of cams associated with said blades, said cams adapted to shift all of said blades and permit their release one by one from shifted position to form card passages between adjacent blades successively. 160
18. In a machine for sorting record cards comprising a plurality of card distributing stations, a plurality of blades adapted when separated to form card passages between adjacent blades, means for shifting all of said blades and permit their subsequent release one by one from shifted position to successively form card passages between adjacent blades, and means under control of the record card for preventing release of certain blades. 165
19. In a machine for sorting record cards comprising a plurality of card distributing stations, a plurality of blades adapted when separated to form card passages between adjacent blades, means adapted to release said blades one by one so as to successively form card passages between adjacent blades, an analyzing mechanism for the record cards and a trigger mechanism under control of the analyzing mechanism for preventing release of certain blades and thereby retaining the separation between adjacent blades to provide a passage for the card analyzed. 170
